United States Patent Office.

MORITZ BACHARACH, OF NEW YORK, N. Y.

Letters Patent No. 98,905, dated January 18, 1870.

IMPROVEMENT IN STREET-URINALS.

The Schedule referred to in these Letters Patent and making part of the same.

To all whom it may concern:

Be it known that I, MORITZ BACHARACH, of the city, county, and State of New York, have invented a new and improved Street-Urinal; and I do hereby declare that the following is a full, clear, and exact description thereof, which will enable others skilled in the art to make and use the same, reference being had to the accompanying drawings, forming part of this specification.

Figure 1 represents a side elevation of my improved street-urinal.

Figure 2 is a side elevation of a modification of the same.

Figure 3 is a vertical transverse section of the same, taken on the plane of the line x x , fig. 1.

Figures 4 and 5 are horizontal sections of the same.

Figure 6 is a diaphragm, showing how the urinals are to be placed in the streets of a city.

Similar letters of reference indicate corresponding parts.

This invention has for its object to design convenient structures, that may be put up in the streets of cities and towns, to contain urinals, and to which easy access can be had from the streets.

In American cities, these necessary structures have scarcely ever been put up, owing to the difficulty of constructing them so as not to occupy much room, and as not to expose those using them.

In European cities, many are arranged, but they are all open toward the street, and exposed to the view of persons in wagons and carriages, although they are closed toward the sidewalks.

My invention consists in constructing the buildings in circular arched form, of wire gauze, lined, for a portion of their height, with sheet-metal, whereby ample provision is made for ventilation, while the occupants are screened from the observation of persons upon the street or sidewalk.

Those which are to be put up at street-corners are in form of an arched passage, as indicated at A in fig. 6, and also in fig. 5, so that the open ends, a a , are in line with the converging curb-stones.

The vessel B is arranged either on the short or on the long side, midway the ends, as shown in fig 5, and is connected with two pipes, b and c , one for the discharge, the other for rinsing-water to flow in.

The ends are closed by doors D D, which are made self-closing, by means of suitable springs or weights.

The men can enter through one door, and leave through the other, so as not to interfere with each other.

By this arrangement, there will be no offence given to the persons on the sidewalk, as they see only the rounded long side of the structure, while, on the street, only the short side and the doors are visible.

Those urinals that have to be put up between street-corners, are made of segmental form, as in fig. 4, and at C in fig. 6. They stand with their long rounded sides on the sidewalk, and their straight sides converge at an angle of about ninety degrees.

Doors are arranged on the straight sides, and a vessel, B, put in, as in the first-described apparatus.

The walls are made of sheet-metal, or other suitable material, and may be of wire gauze, as shown, in which case the lower part of the building has an inner lining, E, to prevent the interior from being inspected from the outside.

The walls are made of wire gauze or netting, as shown, to obtain good ventilation, and their lower parts are provided with an inner lining, of metal, E, to prevent the interior from being inspected from the outside.

Having thus described my invention,
I claim as new, and desire to secure by Letters Patent—

A street-urinal, made on an arc of a circle, or curved transversely, constructed of reticulated material, with a lining in its lower portion, and provided with the basin B and discharge-pipe b , all substantially as described.

MORITZ BACHARACH.
